MOTOR CONTROL SYSTEM

Claude M. Hines, Pittsburgh, Pa., assignor to The
Union Switch & Signal Company, Swissvale,
Pa., a corporation of Pennsylvania

Application February 23, 1939, Serial No. 257,853

10 Claims. (Cl. 172—179)

My invention relates to a motor control system and particularly to an improved system adapted to be employed to control the motor for moving a railway track switch.

5 In some locations it is desirable to employ in the relays or other devices controlling the energizing circuit of the switch motor metal to metal contacts.

10 However, because of the relatively heavy currents present in the circuits controlled by these contacts, there is a possibility that in service the metal to metal contacts may fuse together and fail to separate, and thus fail to interrupt the circuit which they control. If this occurs, 15 it may result in failure of the equipment to operate in the intended manner, and might result in injury to the motor.

15 It is an object of my invention to provide an improved motor control system incorporating 20 means to verify separation of the neutral contacts of a relay employed to control the motor.

A further object of my invention is to provide an improved system of the type described and 25 incorporating means operative to prevent further operation of the motor in the event of failure of the contacts of the motor control relay to separate as intended.

Another object of my invention is to provide an improved control system for the motor for 30 operating a railway track switch, the control system employing a polarized relay having both neutral and polar contacts for controlling the circuit of the switch motor to effect movement of the switch in one direction or the other, the 35 system incorporating auxiliary means for interrupting the circuit of the switch motor in the event of failure of the neutral contacts of the polarized relay to separate in the intended manner.

40 A further object of my invention is to provide an improved switch motor control system of the type described, the system incorporating an auxiliary relay separate from the polarized switch motor control relay and controlling the circuits 45 of the winding of the polarized relay, the circuit of the winding of the auxiliary relay being controlled by the neutral contacts of the polarized switch control relay in such manner that on a change in the polarity of the current supplied 50 to the circuits of the windings of the polarized relay and of the auxiliary relay, the winding of the auxiliary relay cannot thereafter be energized unless the neutral contacts of the polarized relay become released.

55 Another object of my invention is to provide

an improved motor control system employing a first and a second relay to control the circuit of the motor, the first relay being provided with metal to metal contacts and the second relay being provided with infusible contacts, the control system being arranged so that the first relay normally serves to interrupt the motor circuit, and so that the second relay will operate to interrupt the motor circuit if the first relay fails to do so.

10 A further object of my invention is to provide an improved motor control system incorporating a polar relay and a neutral relay for controlling the motor circuit, the polar relay having metal to metal neutral contacts, the neutral relay having infusible contacts, the control system being arranged so that the neutral contacts of the polar relay normally serve to interrupt the motor circuit, and so that the contacts of the 15 neutral relay will interrupt the motor circuit if the contacts of the polar relay fail to do so, the system also being arranged so that if the neutral contacts of the polar relay fail to separate when they should, the contacts of the neutral 20 relay will thereafter remain released and will maintain the motor circuit interrupted.

25 Another object of my invention is to provide an improved switch motor control system.

30 Other objects of my invention and features of novelty will be apparent from the following description taken in connection with the accompanying drawing.

35 I shall describe one form of apparatus embodying my invention and shall then point out the novel features thereof in claims.

40 In the drawing the single figure is a diagram of a motor control system embodying my invention.

45 Referring to the drawing, there is shown there- in a railway track switch W which is movable between a normal and a reverse position by means of an electric motor M. The circuits of the motor M are controlled by a polarized switch control relay WR, an auxiliary slow releasing neutral relay WRP, and an overload relay OR.

50 The windings of the relays WR and WRP are energized by current supplied over control wires 10 and 11, while means is provided to selectively supply current of one or the other relative polarity to the control wires. As shown in the drawing, there is a switch control lever L which is movable between a normal and a reverse position. The lever L has associated therewith contacts 12 and 14 which are constantly connected 55

to terminals B and C, respectively, of a battery 15.

When the lever L is in the normal position N, as shown, contact 12 engages contact 18 to which is connected control wire 10, while contact 14 engages contact 19 to which is connected control wire 11. Accordingly in this position of the control lever L current of one relative polarity, which may be considered as normal polarity, is supplied from battery 15 to control wires 10 and 11.

When the lever L is in the reverse position R, contact 12 engages contact 19, while contact 14 engages contact 20 to which is connected a branch of control wire 10. Accordingly in this position of the lever L current of the opposite or reverse relative polarity is supplied from battery 15 to the control wires 10 and 11.

Control wire 10 is connected to one terminal 20 of the winding of relay WR, and also to one terminal of the winding of relay WRP, while control wire 11 is connected to movable contact 22 of overload relay OR. Contact 22, when released, engages contact 23 which is connected by wire 24 to neutral contact 25 of relay WR, and also to movable contact 26 of relay WRP.

Contact 25 of relay WR, when released, engages contact 32 which is connected by wire 33 to movable contact 34 of relay WRP, to stationary contact 35 of relay WRP and also to a terminal of the winding of relay WRP. Contact 26 of relay WRP, when picked up, engages contact 35 to thereby establish connection from wire 24 to wire 33 leading to the winding of relay WRP, 35 while contact 34 of relay WRP when picked up engages contact 39 which is connected by wire 29 to a terminal of the winding of relay WR.

The relay WR has neutral contacts 40 which are connected by wire 41 to the normal polar 40 contact 42 and to reverse polar contact 43 of the relay. Neutral contacts 40, when picked up, engage contacts 45 which are connected by wire 46 to contacts 48 of relay WRP.

The contacts 40 and 45 of relay WR operate, 45 as hereinafter explained in detail, in the event of an overload of the switch and resultant picking up of the contacts of overload relay OR, or in the event of reversal of the switch in mid stroke, to interrupt the switch motor circuit. It is desired that the contacts 40 and 45 be constructed of metal, and the system provided by this invention is directed to means to prevent injury to the motor, and to prevent subsequent improper operation of the motor and of the associated apparatus, in the event the contacts 40 and 45 of relay WR fuse together and fail to separate on deenergization of the winding of the relay.

The contacts 48 of relay WRP, when picked up, engage contacts 49 which are connected by wire 50 to terminal C of battery 52. The contacts 48 and 49 may either or both be constructed of infusible material so that these contacts cannot fuse together and fail to separate.

The relay WR has a polar contact 53 which is connected by wire 55 to resistance unit 56, and to one terminal of the pick-up winding 58 of overload relay OR. The other terminals of the resistance unit 56 and of the winding 58 of relay OR are connected by wire 59 to one brush of the armature 60 of motor M.

The contact 53 of relay WR, when in the normal position, as shown, engages normal polar contact 61 which is connected by wire 62 to contact 64, while contact 53, when in the reverse position, engages reverse polar contact 43.

The relay WR also has a polar contact 65 which is connected by wire 66 to the other brush of the motor armature 60.

Contact 65, when in the normal position, as shown, engages contact 62, while, when it is in its reverse position, contact 65 engages reverse polar contact 68 which is connected by wire 69 to contact 70.

The switch W has associated therewith a movable contact 72 which is movable in accordance with movement of the switch and which at times engages the contacts 64 and 70. The contacts 64 and 70 are arranged so that contact 72 engages contact 64 in all positions of the switch W except the normal position thereof, while contact 72 15 engages contact 70 in all positions of the switch W except the reverse position thereof.

The switch operated contact 72 is connected by wire 73 to one terminal of the motor field winding 75, the other terminal of which is connected by wire 76 to terminal B of battery 52.

The overload relay OR has a holding winding 77 to one terminal of which is connected a branch of control wire 10, while the other terminal of this winding is connected by wire 79 to contact 25 20 of the relay. Contact 80, when released, engages a contact 81 to which is connected wire 10 to thereby establish a circuit shunting the holding winding 77 and thus render the overload relay slow acting. The circuit shunting the winding 77 is traced from one terminal of the winding through wire 10, contacts 80-81, and wire 10 to the other terminal of the relay winding.

On picking up of contact 80 of relay OR the contact 80 first becomes disengaged from contact 81 to interrupt the circuit shunting the winding 77, while on further movement of the contact 80 it engages contact 22 to thereby establish the circuit for energizing the holding winding 77 from the control wires 10 and 11. On still further 40 upward movement of the contact 80 contact 22 is moved out of engagement with contact 23 to thereby interrupt connection from control wire 11 to wire 24, and thus interrupt energization of the windings of relays WR and WRP.

The resistance unit 56 has a positive thermal coefficient of resistance, that is, the resistance of the unit increases as the temperature of the material of which the unit is constructed increases. The resistance unit 56 and the various parts of the overload relay OR are arranged and proportioned so that under normal conditions most of the current in the circuit of the switch motor M flows through the resistance unit 56, while too little current flows through the pick-up winding 58 of relay OR to cause the contact 80 of the relay to become picked up. Accordingly contact 80 normally remains released.

In the event of an obstruction to movement of the switch so that an unusually heavy current is present in the circuit of the switch motor for an appreciable time interval, the material of which the unit 56 is constructed becomes heated and its resistance increases, thereby increasing the current in the pick-up winding 58 of relay OR 65 to a value effective to cause picking up of the contact 80.

The relay WR may have polar contacts, not shown, which cooperate with switch operated contacts, not shown, in the manner well known in the art, to control the supply of current, and also the polarity of the current supplied, to circuits, such as wires 102 and 104, for indicating the position of the switch W.

The wire 102 is connected to contact 103 of 75

relay WRP, while wire 104 is connected to contact 105 of relay WRP. Contact 103, when picked up, engages a contact 106 to which is connected indication wire 107, while contact 105, when picked up, engages contact 108 to which is connected indication wire 109. The indication wires 107 and 109 lead to suitable means, not shown, for indicating at a remote point, such as at the point at which switch control lever L is located, the position occupied by the switch W.

The contacts of the relay WRP are slow in releasing so that when the windings of the relays WR and WRP are simultaneously deenergized, or when the direction of energization of the windings of these relays is simultaneously reversed, the contacts 40 of relay WR will become released and will interrupt the circuit of the switch motor M before the contacts 48 of relay WRP become released.

20 The equipment is shown in the drawing with the switch W and the switch control lever L in their normal positions, with the windings of relays WR and WRP energized, and with the contact 80 of overload relay OR released.

25 At this time as the switch control lever L is in the normal position, current of normal relative polarity is supplied from battery 15 to the control wires 10 and 11, and as the winding of relay WR is energized with current of normal relative polarity, the neutral contacts 25 and 40 of the relay are picked up, while the polar contacts 53 and 65 of the relay are in their normal positions as shown. As the winding of relay WRP is energized, the contacts of this relay are picked up.

The circuit for energizing the winding of relay WR from the control wires 10 and 11 is traced from wire 11 through contacts 22-23 of relay OR, wire 24, contacts 26-35 of relay WRP, wire 40 33, contacts 34-30 of relay WRP, wire 29, and winding of relay WR to wire 10.

At this time the winding of the relay WRP is energized from the control wires 10 and 11 over its stick circuit which is traced from wire 11 through contacts 22-23 of relay OR, wire 24, contacts 26-35 of relay WRP, wire 33, winding of relay WRP, and wire 10.

As the switch W is in the normal position, contact 72 does not engage contact 64, and hence 50 the normal supply circuit for the switch motor is interrupted.

If at this time the operator wishes to effect movement of the switch W from its normal to its reverse position, he can do so by moving the 55 switch control lever L from its normal to its reverse position.

On this movement of the control lever L to the reverse position, current of reverse relative polarity is supplied to the control wires 10 and 60 11, and therefore to the windings of the relays WR and WRP. On this reversal in the direction of energization of the windings of relays WR and WRP, the neutral contacts of these relays become released, thereby interrupting the previously traced circuits for energizing the relay windings from the control wires 10 and 11.

On release of contact 25 of relay WR, it engages contact 32 which is connected by wire 33 to a terminal of the winding of relay WRP. The 70 winding of relay WRP, therefore, is energized from the control wires 10 and 11 over its pick-up circuit which is traced from control wire 11 through contacts 22-23 of relay OR, wire 24, contacts 25-32 of relay WR, wire 33, winding 75 of relay WRP, and control wire 10.

On picking up of contact 26 of relay WRP it engages contact 35 to thereby establish the previously traced stick circuit for the winding of relay WRP.

On picking up of the contacts of relay WRP, contacts 26 and 34 establish the circuit to energize the winding of the relay WR from control wires 10 and 11. This circuit is traced from wire 11 through contacts 22-23 of relay OR, wire 24, contacts 26-35 of relay WRP, wire 10 33, contacts 34-30 of relay WRP, wire 29, winding of relay WR, and control wire 10.

At this time, therefore, the winding of relay WR will be energized with current of reverse relative polarity, and as a result the polar contacts of this relay will be shifted from their normal to the reverse positions, while the neutral contacts of the relay will become picked up.

On picking up of contact 25 of relay WR the pick-up circuit for the winding of relay WRP is interrupted, but at this time the winding of relay WRP is maintained energized by current supplied over its stick circuit.

On movement of the polar contacts 53 and 65 of relay WR to their reverse positions, and on picking up of the neutral contacts 40 of the relay WR at a time when the contacts 48 of relay WRP are picked up, the reverse supply circuit for the motor M is established, and the motor is operated to move the switch W from the normal to the reverse position.

The reverse supply circuit for the motor M is traced from terminal C of battery 52 through wire 50, contacts 49-48 of relay WRP, wire 46, contacts 45-40 of relay WR, wire 41, contacts 43-53 of relay WR, wire 55, resistance unit 56 and pick-up winding 58 of relay OR in parallel, wire 59, motor armature 60, wire 66, contacts 65-68 of relay WR, wire 69, contact 70, switch operated contact 72, wire 73, motor field winding 75, and wire 76 to terminal B of battery 52.

On movement of the switch W to the reverse position, contact 72 is moved out of engagement with contact 70, thereby interrupting the circuit for energizing the switch motor M with the result that the motor ceases to be operated.

In similar manner if while the switch W is in the reverse position the operator desires to move the switch to the normal position, he can do so by moving the control lever L from the reverse 50 to the normal position. As a result of this movement of the control lever L, current of normal relative polarity is again supplied to the control wires 10 and 11.

On this reversal in the direction of energization 55 of the control wires 10 and 11, and therefore of the windings of relays WR and WRP, the neutral contacts of relay WR become released, while the contacts of relay WRP also become released. On the release of the neutral contacts of relay WRP, the previously traced circuits for energizing the windings of relays WR and WRP from control wires 10 and 11 are interrupted, while on release of contact 25 of relay WR, it engages contact 32 to establish the circuit from wire 24 to wire 33, 65 and thus to complete the pick-up circuit for the winding of relay WRP so that the winding of relay WRP is energized. As a result of energization of the winding of relay WRP, the contacts of this relay become picked up, and on picking up 70 of contact 34, the pick-up circuit for the winding of relay WR is established, and the winding of relay WR is energized with current of normal relative polarity from the control wires 10 and 11.

As a result of this energization of the winding 75

- of relay WR, the polar contacts 53 and 65 of the relay are shifted to their normal positions, while the neutral contacts 25 and 40 of the relay become picked up. On picking up of neutral contact 25 of relay WR, the pick-up circuit for the winding of the relay WRP is interrupted, but at this time the winding of relay WRP is maintained energized by current supplied over its stick circuit which was established on picking up of contact 26.
10. On picking up of the neutral contacts 40 of relay WR, and on movement of the polar contacts 53 and 65 of this relay to their normal positions at a time when the contacts of relay WRP are picked up, the normal supply circuit for the switch motor M is established, and the motor is caused to move the switch W from the reverse to the normal position.

The normal supply circuit for the switch motor M is traced from terminal C of battery 52 through wire 58, contacts 49-48 of relay WRP, wire 46, contacts 45-40 of relay WR, wire 41, contacts 42-65 of relay WR, wire 66, motor armature 60, wire 59, resistance unit 56 and overload relay pick-up winding 58 in parallel, wire 55, contacts 53-61 of relay WR, wire 62, contact 64, switch operated contact 72, wire 73, motor field winding 75, and wire 76 to terminal B of battery 52.

When the switch W reaches the normal position, contact 72 is moved out of engagement with contact 64 to thereby interrupt the normal supply circuit for the switch motor and thus prevent further operation of the motor.

If, while the switch W is being moved from one of its positions to the other, as, for example, from the normal to the reverse position, the operator desires to return the switch to its original position, in this case the normal position, he may do so by returning the control lever to its normal position.

As it is assumed that the switch W is being moved to the reverse position, the control lever L is in its reverse position and current of reverse relative polarity is supplied from battery 15 to the control wires 10 and 11, while the neutral and polar contacts of relay WR and the contacts 48 of relay WRP establish the previously traced reverse supply circuit for the motor M.

On movement of the lever L to the normal position, current of normal relative polarity is supplied to the control wires 10 and 11, while on this change in the polarity of the current supplied to the wires 10 and 11, the neutral contacts of the relays WR and WRP become released and interrupt the circuit of the switch motor. Because of the slow releasing characteristic of the contacts of the relay WRP, the contacts 40 of relay WR release before the contacts of relay WRP release, and hence the circuit of the switch motor is first interrupted by the contacts 40, and is thereafter interrupted at another point by the contacts 48 of the relay WRP.

As the contacts 40 of relay WR become released before contacts 48 of relay WRP become released the circuit of the switch motor is interrupted by contacts 40 of relay WR, so that on release of contacts 48 of relay WR no arcing or burning of the contacts 48 and 49 of relay WRP occurs since the circuit of the switch motor is already interrupted by contacts 40 of relay WR.

On release of contact 25 of relay WR, the pick-up circuit for energizing the winding of relay WRP is established, while on picking up of the contacts of relay WRP, the circuit for energizing the winding of relay WR is established. In addi-

tion, on picking up of the contacts of relay WRP the stick circuit for energizing the relay winding is established so that on subsequent picking up of the neutral contact 25 of relay WR, the winding of relay WRP is maintained energized. 5

As a result of the energization of the winding of relay WR following establishment of the energizing circuit for this relay winding, the polar contacts 53 and 65 are shifted to their normal positions, while the neutral contacts 25 and 40 10 of the relay become picked up with the result that the previously traced normal supply circuit for the switch motor M is established, and the motor operates to move the switch W to the normal position. When the switch attains the normal position, contact 72 is moved out of engagement with contact 64 to interrupt the circuit of the switch motor.

It will be seen that on energization of the winding of relay WRP contacts 48 and 49 of this relay 20 become closed, but at this time the winding of relay WR is deenergized and contacts 40 of relay WR are released. Hence at the time of closing of contacts 48 and 49 of relay WRP no current is flowing in the circuit controlled by these contacts, and, accordingly, no arcing or burning of these contacts occurs.

Furthermore, on subsequent picking up of the contacts 40 of relay WR to complete the circuit of the switch motor M, the contacts 48 and 49 of 30 relay WRP are firmly in engagement so that no arcing between these contacts occurs.

The equipment operates in similar manner if, while the switch W is being moved from the reverse to the normal position, the operator decides 35 to return it to the reverse position. At such times as a result of the reversal in the direction of energization of the control wires 10 and 11 the neutral contacts of the relays WR and WRP become released to interrupt the circuit of the switch motor, while subsequently the contacts of these relays become picked up to reestablish the reverse supply circuit for the switch motor.

As pointed out above the contacts of relay WR release before the contacts of relay WRP become 45 released, while the contacts of relay WR do not become picked up until the contacts of relay WRP are picked up.

If, while the switch W is being moved from one of its positions to the other, as for example from 50 the normal to the reverse position, movement of the switch is obstructed so that the switch cannot complete its movement, the overload relay OR will be operated to interrupt the circuits of the windings of the relays WR and WRP with the 55 result that the neutral contacts of these relays will become released, and will interrupt the circuits of the switch motor M and thereby prevent injury to the motor.

For the purposes of illustration, it will be assumed that the switch W is being moved from the normal to the reverse position, and that further movement of the switch is prevented before the switch reaches the reverse position.

When movement of the switch W is obstructed, 65 the switch motor M draws an abnormally heavy current and the continued flow of this unusually heavy current in the circuit of the switch motor heats the material of which the resistance unit 56 is constructed, thereby increasing its resistance and increasing the flow of current in the pick-up winding 58 of the relay OR.

When this abnormally heavy current flow in the circuit of the switch motor has continued for a predetermined time interval, the contact 80 of 75

5 relay OR becomes picked up, thereby interrupting the circuit shunting the holding winding 77. On further upward movement of the contact 80, it engages contact 81 to thereby establish a circuit for energizing the holding winding 77 from the control wires 10 and 11. This circuit is traced from control wire 10 through winding 77, wire 79, contacts 80-22 of relay OR, and control wire 11.

10 The various parts of the apparatus are arranged so that on energization of the holding winding 77 with current of the polarity supplied at this time from the control wires 10 and 11, this winding assists the pick-up winding 58 to effect picking up of the contact 80, and, accordingly, the contact 80 is moved further towards the picked up position.

15 On this further movement of contact 80, contact 22 is moved out of engagement with contact 23, thereby interrupting connection from control wire 11 to wire 24, and thus interrupting the energizing circuits for the winding of relay WR and also for the winding of relay WRP.

20 On deenergization of the windings of relays WR and WRP occasioned by separation of contacts 22 and 23 of relay OR, because of the slow releasing characteristic of relay WRP, the neutral contacts 40 of relay WR become released before the contacts 48 of relay WRP become released. Accordingly contact 40 of the relay WR interrupts the circuit of the switch motor M and thus prevents injury to the motor which might result from continued energization thereof at a time when movement of the switch W is obstructed.

25 30 On subsequent opening of the contact 48 of relay WRP, the circuit of the switch motor has already been interrupted, and hence no arcing or burning of these contacts occurs.

35 At this time, following interruption of the switch motor circuit by the relays WR and WRP, the contact 80 of overload relay OR continues to be maintained picked up by the holding winding 77, which is energized by current supplied from the control wires 10 and 11 over the circuit established by contacts 80-22 of the relay.

40 On the occurrence of the obstruction to movement of the switch W and operation of the overload relay OR to cause the relays WR and WRP to interrupt the switch motor circuit, the operator 45 may thereafter return the switch W to the position from which it was being moved when movement of the switch was obstructed.

45 In this example, the switch is to be returned to the normal position, and to effect this movement of the switch the control lever L is moved from its reverse to its normal position.

50 On this movement of the control lever L to the normal position, there is a reversal in the direction of energization of the control wires 10 and 11, and, therefore, in the direction of energization of the holding winding 77 of the overload relay OR.

55 On this reversal in the direction of energization of the winding 77, the contact 80 of overload relay OR becomes released, thereby interrupting the circuit for energizing the holding winding 77, while contact 80 again engages contact 81 to establish the circuit shunting the holding winding. On release of contact 80 and resultant movement of the contact out of engagement with contact 22 to interrupt the circuit for energizing holding winding 77, the winding will not thereafter again become energized and hence the contact 80 will remain released.

60 65 70 75 As a result of the release of contact 80 of over-

load relay OR, contact 22 is moved into engagement with contact 23 to thereby establish connection from control wire 11 to wire 24. At this time since the contact 25 of relay WR is released connection is established from wire 24 5 to wire 33 leading to one terminal of the winding of auxiliary relay WRP, and, accordingly, the winding of relay WRP is energized and the contacts of this relay become picked up and establish the stick circuit for the relay winding. 10

15 On picking up of the contacts of relay WRP, the energizing circuit for the winding of relay WR is established and contacts of relay WR become picked up, while as the relay winding is energized with current of normal relative polarity, the polar contacts of the relay are shifted to their normal positions to thereby complete the previously traced normal supply circuit for the switch motor M.

20 In addition on picking up of the neutral contact 25 of relay WR, the pick-up circuit for the winding of relay WRP is interrupted.

25 On completion of the normal supply circuit for the switch motor M, the motor is operated to return the switch W to the normal position, that is, to move the switch W away from the obstruction which prevented its movement to the reverse position. When the switch W attains the normal position, contact 72 is moved out of engagement with contact 64 to interrupt the circuit of the switch motor. 30

35 It will be seen that in the event of an overload of the switch motor and resultant operation of the overload relay, the contacts 40 of the relay WR become released before contacts 48 of relay WRP become released. This sequence of operation takes place because the contacts of the relay WRP are slow in releasing.

40 Since the neutral contacts of relay WR release before the contacts of relay WRP become released, the switch motor circuit is interrupted by the contacts of relay WR and not by the contacts of relay WRP.

45 In like manner, on subsequent completion of the circuit of the switch motor, either following an overload or during normal operation of the equipment to effect movement of the switch, the contacts of relay WRP become picked up before the neutral contacts of relay WR become picked up, and hence the circuit of the switch motor is incomplete at the time the contacts 48 of relay WRP engage contacts 49. Accordingly no arcing or burning of these contacts will result. 50

55 The equipment operates in a similar manner in the event of an overload when the switch W is being moved to the normal position. At this time the overload relay OR will operate as previously described to interrupt the energizing circuits of the windings of relays WR and WRP, and these relays will operate to interrupt the switch motor circuit. On subsequent movement of the switch control lever L to the reverse position, the contact of the overload relay OR becomes released and reestablishes the circuits for energizing the windings of relays WR and WRP, and these relays operate as previously described to establish the reverse supply circuit for the switch motor M with the result that the motor returns the switch W to the reverse position. 60 65

70 In the event the neutral contacts 40 and 45 of relay WR fuse together so that they fail to separate when they should separate, this system operates in such manner that the winding of relay WRP cannot thereafter be energized, and, accordingly, the contacts of relay WRP remain re-

leased to interrupt the circuit of the switch motor, and to also prevent energization of the winding of relay WR to thereby prevent a change in the position of the polar contacts of relay WR.

5 As previously pointed out, the neutral contacts of relay WR should become released when the polarity of the current supplied to the control wires 10 and 11 is changed, or when the circuit of the relay winding is interrupted by operation 10 of the overload relay OR.

For purposes of illustration, it will be assumed that the neutral contacts 40 and 45 of relay WR fuse together at a time when the relay winding is energized with current of normal relative polarity, and that on the subsequent supply of current of reverse relative polarity to the control wires 10 and 11, the contacts of relay WR fail to separate.

On a change in the polarity of the current 20 supplied to control wires 10 and 11, there is a reversal in the direction of energization of the winding of relay WRP and the neutral contacts of this relay become released.

On release of contact 26 of relay WRP, connection 25 from wire 24 to wire 33 is interrupted, thereby interrupting the stick circuit for the winding of relay WRP. At this time, as it is assumed that the neutral contacts 40 and 45 of relay WR are fused together, the neutral armature of the 30 relay will be held in its picked-up position and contact 25 will be held out of engagement with contact 32 so that the pick-up circuit for the winding of relay WRP is interrupted. Accordingly on release of the contacts of relay WRP, 35 the circuit for energizing the relay winding is interrupted, and hence once the relay contacts are released, they will not thereafter again become picked up until contact 25 of relay WR becomes released.

40 On release of the contacts of relay WRP the circuit for energizing the winding of relay WR is interrupted. Accordingly on the supply of current of reverse relative polarity to the control wires 10 and 11, the winding of relay WR 45 will not be energized with current of reverse relative polarity and the neutral contacts of the relay will remain in their normal positions.

As long as the neutral contacts of relay WR remain fused together, and, therefore, remain in 50 their picked up positions so that contact 25 is held out of engagement with contact 32, the winding of relay WRP cannot be energized, and hence the contacts 48 of this relay will remain released and will interrupt the circuit of the 55 switch motor.

In addition contacts 103 and 105 of the relay WRP will be released and will interrupt the supply of current to the indication wires 107 and 109 and the indication means controlled by these 60 wires will fail to provide an indication and the operator will thereby be informed that the equipment is not functioning in the intended manner.

In order to restore normal control of the switch 65 W to the control lever L, it is necessary to first separate the neutral contacts of relay WR and thereby cause contact 25 to engage contact 32 and thus establish the pick-up circuit for the winding of relay WRP. The contacts of relay 70 WRP will thereupon become picked up and will establish the circuit for energizing the winding of relay WR, while the equipment will thereafter operate in the manner described in detail above.

The apparatus operates in a similar manner 75 if on picking up of contact 80 of overload relay

OR, the neutral contacts of relay WR fail to separate. Under these conditions, on picking up of contact 80 of relay OR, the windings of relays WR and WRP will be deenergized. The contacts of relay WRP will become released and contacts 48 of the relay will interrupt the circuit of the switch motor and thus prevent injury to the switch motor.

On subsequent reversal in the polarity of the current supplied to the control wires 10 and 11, 10 the contact 80 of relay OR becomes released and reestablishes connection from control wire 11 to wire 24. As the neutral contacts of relay WR are assumed to be held in their picked-up positions, contact 25 of relay WR will be maintained picked 15 up thereby interrupting the pick-up circuit for the winding of relay WRP. Accordingly the winding of relay WRP will remain deenergized and will maintain the circuit of the switch motor interrupted. As explained above, the contacts 20 of relay WRP will remain released until the contact 25 of relay WR is released.

It will be seen that the auxiliary relay WRP employed in the system provided by my invention checks the release of the neutral contacts 25 of relay WR, and, if for any reason the neutral contacts of relay WR fail to release when they should, the contacts of relay WRP will interrupt the motor circuit and prevent further operation of the switch motor until the relay WR is caused 30 to function in the intended manner.

It will be seen also that under normal operating conditions, when all of the equipment is functioning as intended, the circuit of the switch motor is interrupted by the switch operated contact 72 and the associated stationary contacts. In the event of operation of the overload relay OR or in the event the switch is reversed when in mid stroke, the circuit of the switch motor is interrupted by the neutral contacts 40 and 45 of 40 the relay WR. The contacts 40 and 45 of relay WR are constructed of metal and are adapted to be employed to interrupt the circuit of the switch motor.

The neutral contacts 48-49 of relay WRP, 45 which are constructed of infusible material, ordinarily do not interrupt the circuit of the switch motor when current is present in this circuit. Accordingly no arcing or burning or other injury occurs to these contacts. In the event, 50 however, the neutral contacts of relay WR fuse together and fail to separate when they should, the contacts 48 and 49 of relay WRP will interrupt the switch motor circuit, but this will be so infrequent that the damage to the contacts will 55 be negligible.

Although I have herein shown and described only one form of motor control system embodying my invention, it is understood that various changes and modifications may be made there- 60 in within the scope of the appended claims without departing from the spirit and scope of my invention.

Having thus described my invention, what I claim is:

1. In a motor control system, in combination, an electric motor, a first relay and a second relay, a supply circuit including contacts of both of said relays for energizing said motor, said relays being operable when energized to establish 70 said supply circuit and being operable when de-energized to interrupt said supply circuit, and common means for energizing said relays, the contacts of the first relay being constructed of fusible material, the contacts of the second re- 75

lay being formed of material such that the contacts are infusible, the relays being arranged and proportioned so that when both are simultaneously deenergized the contacts of the second relay will remain closed until after the contacts of the first relay are separated.

2. In a motor control system, in combination, an electric motor, a first relay and a second relay, a supply circuit including contacts of both of said relays for energizing said motor, a control circuit for energizing said relays, and means for supplying current to said control circuit, the contacts of the first relay being formed of fusible material, the contacts of the second relay being formed of material such that the contacts are infusible, the relays being arranged and proportioned so that on a variation in the current in the control circuit to effect opening of the relay contacts the contacts of the second relay will remain closed until after the contacts of the first relay become opened.

3. In a motor control system, in combination, an electric motor, a first relay and a second relay, a supply circuit including contacts of both of said relays for energizing said motor, said relays being operable when energized to establish said supply circuit and being operable when deenergized to interrupt said supply circuit, a control circuit for energizing said relays, and means for supplying current to said control circuit, the contacts of the first relay being formed of fusible material, the contacts of the second relay being formed of material such that the contacts are infusible, the relays being arranged and proportioned so that when both are simultaneously deenergized the contacts of the second relay will remain closed until the contacts of the first relay become opened.

4. In a motor control system, in combination, an electric motor, a first relay and a second relay, a supply circuit including contacts of both of said relays for energizing said motor, said relays being operable when energized to establish said supply circuit and being operable when deenergized to interrupt said supply circuit, a control circuit for energizing said relays, and means for supplying current to said control circuit, the contacts of the first relay being formed of fusible material, the contacts of the second relay being formed of material such that the contacts are infusible, the contacts of the second relay being slow in releasing so that when said relays are simultaneously deenergized the contacts of the second relay will not become opened until after the contacts of the first relay have become opened.

5. In a motor control system, in combination, an electric motor, a first relay and a second relay, a supply circuit including contacts of both of said relays for energizing said motor, said relays being operable when energized to establish said supply circuit and being operable when deenergized to interrupt said supply circuit, a control circuit through which current may be supplied to energize said relays, means for supplying current to said control circuit, a pick-up circuit for energizing the second relay from said control wires, said circuit being controlled by a contact of the first relay and being complete when and only when the contacts of the first relay are released, a stick circuit for energizing the second relay from said control circuit, said stick circuit being complete when and only when the contacts of the second relay are picked up, and a circuit including a contact of the second

relay for energizing the first relay from said control circuit, said circuit being complete when and only when the contacts of the second relay are picked up, the contacts of the second relay being slow in releasing so that when the relays are simultaneously deenergized the contacts of the second relay will not become released until after the contacts of the first relay become released.

6. In a motor control system, in combination, an electric motor, a polarized relay having neutral and polar contacts, a neutral relay, a supply circuit including neutral contacts of the polar relay and contacts of the neutral relay for energizing said motor, the polar contacts of the polar relay also controlling the supply circuit to effect operation of the motor in one direction or the other, a control circuit through which current may be supplied to energize said relays, means for supplying current of one polarity or the other to said control circuit, a pick-up circuit for energizing the neutral relay from said control circuit, said pick-up circuit being controlled by a neutral contact of the polar relay and being complete when and only when said contact is released, a stick circuit for energizing the neutral relay from said control circuit, said stick circuit being controlled by contacts of the neutral relay and being complete when and only when said contacts are picked up, and a circuit complete when and only when the contacts of the neutral relay are picked up for energizing the polar relay from said control circuit, the contacts of the neutral relay which control the motor supply circuit being formed of material such that they are infusible, the neutral contacts of the polar relay which control the motor supply circuit being formed of fusible material, the contacts of the neutral relay being slow in releasing so that when both relays are simultaneously deenergized or when the polarity of the current supplied to said control circuit is changed the contacts of the neutral relay will remain closed until after the neutral contacts of the polar relay become released.

7. In a motor control system, in combination, an electric motor, a polarized relay having neutral and polar contacts, a neutral relay, a supply circuit including neutral contacts of the polar relay and contacts of the neutral relay for energizing said motor, the polar contacts of the polar relay also controlling the supply circuit to effect operation of the motor in one direction or the other, a control circuit through which current may be supplied to energize said relays, means for supplying current of one polarity or the other to said control circuit, and means for energizing said relays with current supplied from said control circuit, the contacts of the neutral relay which control the motor supply circuit being formed of material such that the contacts are infusible, the neutral contacts of the polar relay which control the motor supply circuits being formed of fusible material, the contacts of the neutral relay being slow in releasing so that when the relays are simultaneously deenergized or when the polarity of the current supplied to the control circuit is changed the contacts of the neutral relay will remain closed until the neutral contacts of the polar relay become opened.

8. In a motor control system, in combination, an electric motor, a polarized relay having neutral and polar contacts, a neutral relay, a supply circuit including neutral contacts of the polar relay and contacts of the neutral relay for ener-

gizing said motor, the polar contacts of the polar relay also controlling the supply circuit to effect operation of the motor in one direction or the other, a control circuit through which current may be supplied to energize said relays, means for supplying current of one polarity or the other to said control circuit, means for energizing said relays with current supplied from said control circuit, and an overload relay governed in accordance with the magnitude of the current flowing in said supply circuit, said overload relay controlling said control circuit, the contacts of the neutral relay which control the motor supply circuit being formed of material such that the contacts are infusible, the neutral contacts of the polar relay which control the motor supply circuit being formed of fusible material, the contacts of the neutral relay being slow in releasing so that when the relays are simultaneously deenergized or when the polarity of the current supplied to the control circuit is changed the contacts of the neutral relay will remain closed until the neutral contacts of the polar relay become opened.

9. In a motor control system, in combination, an electric motor, a first relay and a second relay, a supply circuit including contacts of both of said relays for energizing said motor, a control circuit for energizing said relays, means for supplying current to said control circuit, and an overload relay governed in accordance with the magnitude of the current flowing in said supply

circuit, said overload relay controlling said control circuit, the contacts of the first relay being formed of fusible material, the contacts of the second relay being formed of material such that the contacts are infusible, the relays being arranged and proportioned so that on a variation in the current in the control circuit to effect opening of the relay contacts the contacts of the second relay will remain closed until after the contacts of the first relay become opened. 10

10. In a motor control system, in combination, an electric motor, a first relay and a second relay, a supply circuit including contacts of both of said relays for energizing said motor, said relays being operable when energized to establish said supply circuit and being operable when deenergized to interrupt said supply circuit, common means for energizing said relays, and an overload relay governed in accordance with the magnitude of the current flowing in said supply circuit, said overload relay controlling the means for energizing said first and second relay, the contacts of the first relay being constructed of fusible material, the contacts of the second relay being formed of material such that the contacts are infusible, the relays being arranged and proportioned so that when both are simultaneously deenergized the contacts of the second relay will remain closed until after the contacts of the first relay are separated. 15 20 25 30
